UNITED STATES PATENT OFFICE

LYNUS CLYDE REYNOLDS, OF SWEETWATER, TENNESSEE, ASSIGNOR TO THE TABULATING MACHINE COMPANY, OF ENDICOTT, NEW YORK, A CORPORATION OF NEW JERSEY.

TABULATING MACHINE

Application filed August 13, 1930. Serial No. 474,927.

- This invention relates to tabulating machines and more particularly to those controlled by perforated record cards. It is the primary object of the present invention to 5 provide an automatic control device for controlling the operation of a tabulating typewriter of the type disclosed in applicant's Patent No. 1,519,054, issued December 9, 1924.
- 10 The device provides contacting mechanism adapted to sense the perforations in a particular field of a record card in advance of the regular data sensing devices to determine whether the card belongs to the group being 15 tabulated. The detection of a change in group number will cause the cessation of machine operation if all cards being run through the machine have been pre-sorted to the same group number. The stoppage of the machine 20 will be an indication that there has been an error in sorting and the misplaced card may be removed before the data thereon has been accumulated with the data of the preceding cards.
- 25 A further object resides in the provision of a novel contact device past which the cards are movable transversely of the columns thereof and including an arrangement whereby the circuits for controlling can be opened 30 or rendered inoperative for certain columns of the cards which are not used for automatic control.
- Further and other objects and advantages 35 will be hereinafter set forth in the accompanying specification and claims, and shown in the drawing, which by way of illustration shows what is now considered to be the preferred embodiment of the invention.
- Fig. 1 is a diagrammatic view of the apparatus. 40 Fig. 2 is a cross section of the automatic control drum and selectively operated sliders.
- In the drawing, 10 represents the solenoids which are suitably connected to the tabulating devices of the tabulator in a manner fully disclosed in the patent referred to. The punched cards 11 are fed from a convenient magazine by a reciprocatory picker 12, one by one in a longitudinal direction 45 into cooperation with a control drum 13 and an analyzing drum 14. These drums are driven in unison by a motor 15 and are spaced apart so that the field of the card bearing control number perforations will be sensed by brushes 16 before the data fields are analyzed by brushes 17. It is obvious that by spacing the drums further apart, the entire card may be sensed by brushes 16 before the leading edge of the card encounters brushes 17. The drums have a rolling contact with the cards as they pass by and feed rollers (not shown) may be provided to assist in moving the cards through the machine. The manner in which the cards are successively fed past the brushes is fully shown and described in Patent No. 1,519,054 and need not be further explained here. Suffice it to say that for each card passed through the machine drums 13 and 14 will make one complete revolution, making rolling contact with the surface of the cards and cooperating with each card in like manner so that a particular point on a drum will contact with the same point on each card. 55
- Drum 13 is constructed of insulating material and has its circumference slotted to receive a plurality of sliders 18, fitting into wedged shaped slots which restrain the sliders against radial displacement. A contacting sleeve 19 has a flange 20 engaging the inner edge of the various sliders 18. The brush 21 is constructed so as to have a wiping contact against the end of the sleeve 19, as the drum 13 rotates. 60
- Each slider 18 has a projection 22 and the same is manually slideable in an axial direction to bring the projection 22 into alignment with any one of the brushes 16, said brushes being arranged in a series transversely of the cards and parallel with sliders 18. The brushes can contact projections 22 through the perforations in the cards for closing the circuits which maintain the machine in operation. 65
- The device has been shown as being adapted to control machine operations through a single column and by means of the selective arrangement of sliders 18, the particular slider selected to correspond to the controlling column of the card may be moved to 70
- 100

5 presents its projection 22 to the brush 16 corresponding to the index point position in which a perforation should occur. The remaining sliders 18 are moved to their extreme
 10 left-hand position as viewed in Fig. 2 where they are out of cooperation with brushes 16. A contact cam 23 mounted upon the pivot shaft of drum 13 is then adjusted so that it will open its contact 24 at the time in the
 15 cycle of operations when the selected control column is at the brush 16. If there is a correct perforation in this column, the machine will continue to operate, but if no perforation is present in the index position in question or one is present in some other index position, the operating circuit will be interrupted and the machine will stop before the data has been sensed by the analyzing brushes 17 so that the operator may remove the card.
 20 Referring now to the electric circuit of the machine, the disk 25 of drum 14 is connected directly by wires 26 and 27 to one side of battery 28 and analyzing circuits will be completed through the data field of the card
 25 by brushes 17 connected to solenoids 10 which in turn are connected through wire 9 to the other side of battery 28. The function of solenoids 10 is well explained in the above mentioned patent.
 30 One brush or terminal of the motor 15 is connected to wires 29 and 30 extending from battery 28 while wire 31 leading from the other brush or terminal of the motor is connected to one of a pair of contacts 32. The
 35 other contact of said pair being connected to wire 33 so that the switch 34 controls the circuit 31-33. Wire 33 terminates in one of a pair of contacts 35, the other contact of which is connected to a wire 36, and a switch 37 connects the two contacts 35 to complete the circuit 33-36.
 40 As explained in the patent referred to, the typewriter carriage at the completion of each cycle of operations under control of a card
 45 will bring a pointer 38 against the contact 39 which will close the circuit of magnet 40 and thereby move switch 37 away from the contacts 35. This will open the circuit of motor 15 which includes battery 28, wire 29, motor 15, wire 31, contacts 32, wire 33, contacts 35 and wires 36 and 27. This interruption of the motor circuit will cause stoppage of the drums 13 and 14. The motor 41 is thereupon brought into operation so as to return the carriage. This circuit is completed through the switch 37 from battery 28, wire 30, contacts 50, motor 41, wires 43 and 27 back to battery 28. The motor 41 will cause return of the carriage in a known manner and upon completion of its movement the carriage will cause a tripping member disclosed in the patent to move against switch 37 and rock the switch back against the contacts 35 thereby stopping motor 41 and again bringing the motor 15 into operation.
 50
 55
 60
 65

This will continue the movement of the cards by bringing the next card into position between drum 13 and brushes 16 to sense the control column.

The arrangement and timing of the device 70 is such that during the above feeding cycle the brushes 16 traverse the control column before the data field is presented to the brushes 17 for analysis and control of the accumulating mechanism. If the correct perforation is presented, the opening of contact 24 will be prevented from breaking the normally closed circuit of magnet 42. This circuit extends from battery 28, wires 27 and 43, magnet 42, wire 44 to normally closed 75 contact 24 and thence through wires 45, 46 and 30 back to battery. Contact 24 is adapted to open at the instant the selected column is presented to the brushes 16 so that if the correct perforation is presented the circuit through the contact will be shunted from the magnet 42 through wire 47, brush 16, hole in the card, projection 22, slider 18, sleeve 19, brush 21, wires 46 and 30 back to battery.
 80

The absence of the perforation at the selective index point position will not shunt contact 24 at its breaking position and consequently the circuit through magnet 42 is broken and its armature switch will be rocked under the influence of its spring to 90 open contacts 32. The opening of these contacts in turn will interrupt the circuit to motor 15 and the device will cease operating. This is a signal to the operator that a card having a different control perforation than those being tabulated is presented to brushes 100 100 and the operator will be apprised that the first card of the new group is present and may therefore proceed to totalize the foregoing cards, and clear the accumulators preparatory to entering information from the new group or perform such other functions as are consistent with automatic controlling of machines of this character.
 105

A key contact 51 is provided, which when 110 closed will cause energization of magnet 42 and resumption of operation of the machine after the slider 18 has been moved to operate with the new controlling index point position.
 115

While there has been shown and described and pointed out the fundamental novel features of the invention as applied to a single modification, it will be understood that various omissions and substitutions and changes 120 in the form and details of the device illustrated and in its operation may be made by those skilled in the art without departing from the spirit of the invention. It is the intention therefore to be limited only as indicated by the scope of the following claims:
 125

1. In a machine of the class described, a plurality of analyzing devices for sensing perforations in columns of a record card which is adapted to be fed transversely of 130

the columns thereof past said analyzing devices, a member movable with said card and having a selectively positionable contacting device adapted to be positioned for registration with a single one of said analyzing devices, through a perforation in the card and means for controlling the operation of the machine as an incident to the registration of said contact and the selected analyzing device through a perforation in the card.

5 2. In combination a tabulating machine having means therein for successively and continuously feeding record cards transversely of the columns thereof, an automatic control device provided with settable means for sensing the perforations in said cards column by column and for interrupting the continuous card feed when the perforations in the card do not agree in arrangement with 10 the setting of said settable means.

3. In a card controlled machine of the class described in combination, a tabulating machine, analyzing means for successively analyzing the columns of perforated record 15 cards to control said tabulating machine, a settable automatic control device positionable to cooperate with a selected index point position in a selected card column and means controlled by said control device for preventing the further operation of said tabulating machine when said device fails to 20 register with a perforation in the selected card column index point position.

4. In a card controlled machine of the class 25 described, in combination a tabulating machine for accumulating items from record cards, and provided with means for continuously and successively feeding cards therethrough transversely of the columns thereof, a settable control device adapted to move synchronously with the cards, means for comparing the arrangement of the perforations of said cards with said settable device, and means called into operation by 40 said device for interrupting the continuous card feed when a card is unlike the settable device in the arrangement of its control perforations.

5. In a machine of the class described 50 having feeding mechanism adapted to feed cards continuously and successively in a direction transversely of the columns thereof, a series of brushes, one for each index point position adapted to analyze the cards column by column as they progress through the machine, a drum moving in synchronism with the card and having a contacting slider, positionable to cooperate with any one of said brushes, a machine controlling circuit adapted 55 to be completed between said brushes and slider through a perforation in the record card and means for interrupting said circuit upon failure of said slider to cooperate with said brush due to the absence of a perforation 60 in the preselected index position.

6. In a machine of the class described adapted to feed record cards transversely of the columns thereof, a set of analyzing brushes, a supplemental set of control contact brushes for the cards so arranged relatively to the other brushes that said supplemental brushes sense control hole perforations before data perforations arrive at the analyzing brushes, a drum having contacting sliders positionable to conform to the location of control positions on the card, means for moving said sliders into column by column cooperation with the card, a circuit adapted to be completed through the control perforations between the supplemental brushes and the sliders and to be interrupted if the locations of perforations do not agree with the location of the sliders.

7. In a machine of the class described in 70 claim 6 in combination therewith, a magnet in said circuit and contacts controlled by said magnet to control the operation of the machine.

In testimony whereof I hereto affix my 75 signature.

LYNUS CLYDE REYNOLDS.
